FABRICATED BLADED COMPRESSOR WHEELS

Edward A. Stalker, Bay City, Mich., assignor to The Stalker Corporation, a corporation of Michigan

Filed Feb. 10, 1955, Ser. No. 487,315

4 Claims. (Cl. 253—39)

This invention relates to bladed wheels for axial flow compressors.

An object of the invention is to provide a light weight wheel which is economical to fabricate.

Another object is to provide a bladed wheel particularly adapted to relatively small diameters.

Other objects will appear from the description, drawings and claims.

The above objects are accomplished by the means illustrated in the accompanying drawings in which:

Fig. 1 is a fragmentary axial section of a compressor according to this invention;

Fig. 2 is an enlarged fragmentary section of a wheel on line 2—2 in Fig. 3;

Fig. 3 is an enlarged fragmentary axial section of a bladed wheel of the compressor of Fig. 1;

Fig. 4 is a front axial view of a bladed wheel;

Fig. 5 is a side elevation of a blade according to this invention; and

Fig. 6 is a fragmentary section on line 6—6 in Fig. 3.

In relatively small compressors of the axial flow type, the cost of fabrication is particularly important. The cost of the blades can be kept low by employing similar blade sections of equal chord throughout the blade span. Such blades can be economically produced as solid ones by rolling a solid strip of the proper blade section and then cutting to length. To obtain a low cost the blades should be provided with simple economical means of retention in a wheel. Such means is also provided by this invention.

Referring now to the drawings, a compressor and its components are indicated generally by 10 in Figs. 1—6. The case is 12 which has the annular inlet 14 and annular exit 16. It houses the wheel assembly 20 mounted for rotation by the shafts 22 and 24 in bearings 26 and 28.

The wheel assembly comprises the wheels 30—32, and since the type of construction is similar for all wheels only wheel 31 will be described in detail.

A fragmentary section of wheel 31 is shown in Fig. 3. It comprises the air foil blade portions 40 which are integral with and extend radially outwardly of, root portions 41, the blades being peripherally spaced about the hub means 42 with wheel flow passages 43, Fig. 2, between them. In the present instance this means includes one or more disks which are let into slots in the inner ends of the blade roots. Thus as shown particularly in Fig. 3 the disks 44 and 46 each has a radial portion fixed respectively in slots 50 and 52. See Figs. 1, 3 and 5. There are also the intermediate disks 54 and 56 whose outer ends are fixed in slot 58 and whose inner ends are fixed to the inner ends of the disks 44 and 46, preferably by solder or other fused metal between the parts, thus bridging the gap between disks 44 and 46.

As shown particularly in Figs. 1, 3 and 4, each wheel has the teeth 60, Fig. 4, cut in the disk about the central

2

hole 62. These teeth fit into the flutes 64 between the splines 66 in the cylinder 68.

The wheels are positioned apart by the rings 65 shown in Figs. 1 and 3.

Shaft means for driving the wheels comprise end disks 70 and 72 integral with shafts 22 and 24 respectively, and the cylinder 68 to which the disks are attached by screws 74.

Preferably the disks 44, 46, 54 and 56 do not extend outward beyond the inner surface 80 of one (or both) of the flanges 82 of the generally cylindrical rim means 84 so that it can preferably be slid axially over the disks as an integral ring. This assures a strong and cheap rim means.

15 The blades are then inserted radially through apertures in the rim means and as shown in Fig. 6 each blade is preferably fixed to the rim means 84 by fillets of solder or fused metal 90, also to the disks by similar fillets 92. Each blade is also preferably fixed to the front and rear flanges of the rim means by fused metal at 93 and 94. 20 Stators 100—102 are interposed between the wheels as shown in Figs. 1 and 3. These are preferably supported from the compressor case 12.

25 Although the invention is particularly adapted to blades of constant blade section throughout it is not limited to these but may be used with any type blade.

The rim means and the disks are readily made as sheet metal constructions, that is they are readily cut out from sheet stock and formed to shape by pressing with dies.

30 This invention refers to compressor wheels for increasing the static pressure and density of an elastic fluid. In order to achieve a significant change in density with an axial flow compressor each wheel must be operated at a speed high enough to effect a significant change in density, 35 that is a change which in magnitude is outside the usual order of engineering accuracy in industry. Thus machines are considered to be compressors as distinguished from fans or blowers at tip speeds of about 400 feet per second or more. At such a speed the average change in density 40 along the blade length is about 3% which is just about the common order of accuracy of measurement of the density. Such compressors are expected also to operate at blade tip speeds close to the velocity of sound. At such speeds the change in pressure may be more than 45 70% or more than 10 pounds per square inch for air inducted at atmospheric pressure.

50 Since in a compressor wheel there is a substantial pressure variation from front to rear the ratio of the hub radius to the blade tip radius is relatively large of a value 55 of the order of 0.5 and preferably greater so that the pressure difference between front and rear sides can be sustained without a return flow at the hub such as occurs in a fan. For the same reason the blades are spaced peripherally close together, preferably about one chord length or less apart.

55 Commonly half to all the static pressure change occurs in the wheel between the leading and trailing edges. To sustain such a change in pressure along the wheel passages from leading to trailing edges of the blades the 60 hub rim between adjacent blades and from leading to trailing edges is a fair and continuous surface. Also at all rotative speeds the case must fit closely about the blade tips which are contoured to the cylindrical surface of the case along substantially the whole tip length of the blade 65 chord.

65 To diffuse the flow between blades and achieve a pressure change the flow should follow the blade surfaces without eddies. Accordingly the blades should have fared or tapered leading edges. They should have 70 sharpened trailing edges to be efficient.

It is commonly understood in engineering and industry

that sheet metal construction is limited to sheets whose planar dimensions are large in comparison to their thicknesses for thicknesses less than about $\frac{1}{16}$ of an inch. Sheets of greater thickness are called plates. (Steel sheet and plate manufacturers list their product of large planar dimensions of $\frac{3}{16}$ or less as sheets and greater thicknesses as plates.) Sheet metal constructions are comprised of parts which are formed from sheet material to define the contours of the part in the plane of the sheet, and of such parts which are subsequently given another shape by pressing with a die.

It will now be clear that I have disclosed a novel wheel structure for compressors which is of light weight and economical to produce.

While I have illustrated specific forms of the invention, it is to be understood that variations may be made therein and that I intend to claim my invention broadly as indicated by the appended claims.

I claim:

1. In combination in a bladed wheel for exchanging energy with a fluid, a hub structure comprising a plurality of axially spaced disks having peripherally continuous and imperforate radial outer portions secured together for rotation about the axis of symmetry thereof, a plurality of blades peripherally spaced about said hub structure, each said blade having axially spaced slots each receiving said radially outer imperforate portion of each of said disks thereinto, said blades being fixed to both sides of said outer imperforate portions of said disks by fused metal, and continuous annular rim means defining wheel flow passages between adjacent blades, said rim means being fixed in said wheel at the inner end portions of said blades and extending from one blade to another providing walls bounding said wheel flow passages on the radially inward sides thereof, said rim means having front and rear flanges directed radially inward, the inner end of at least one of said flanges having a radius greater than that of said disks to provide for axial assembly thereover.

2. In combination in a bladed wheel for exchanging energy with a fluid, a hub structure comprising a plurality of axially spaced disks having peripherally continuous and imperforate radial outer portions secured together for rotation about the axis of symmetry thereof, a plurality of blades peripherally spaced about said hub structure, each said blade having axially spaced slots each receiving said radially outer imperforate portion of each of said disks thereinto, said blades being fixed to both sides of said outer imperforate portions of said disks by fused metal, and continuous annular rim means defining wheel flow passages between adjacent blades, said rim means being fixed in said wheel radially outwardly of said disks at the inner end portions of said blades and extending from one blade to another providing walls bounding said wheel flow passages on the radially inward sides thereof, said rim means having front and rear flanges directed radially inward and fixed by fused metal to each said blade along the front and rear edges thereof, the inner end of at least one of said flanges having a radius greater than that of said disks to provide for axial assembly thereover.

5 3. In combination in a bladed wheel for exchanging energy with a fluid, a hub structure comprising a plurality of axially spaced disks having peripherally continuous and imperforate radial outer portions secured together for rotation about the axis of symmetry thereof, a plurality of blades peripherally spaced about said hub structure, each said blade having axially spaced slots each receiving said radially outer imperforate portion of each of said disks thereinto, said outer imperforate portions being fixed to both sides of said blades by fused metal at said slots, and continuous annular rim means defining wheel flow passages between adjacent blades, said rim means being fixed in said wheel at the inner end portions of said blades and extending from one blade to another providing walls bounding said wheel flow passages on the radially inward sides thereof, each said blade having similar blade sections of equal chord lengths over a major portion of the blade length radially outward from said rim means, said rim means having a radius greater than that of said disks and being assembled thereover and located radially outwardly thereof.

10 4. In combination in a bladed wheel for exchanging energy with a fluid, a hub structure comprising a plurality of disks spaced along an axis of rotation and having peripherally continuous and imperforate outer portions, a continuous annular rim means encircling said disks and spaced radially outward therefrom to be slid axially over said disks, said rim means having an axial length corresponding to the axial length of said wheel, a plurality of blades peripherally spaced about said rim means with their spans extending radially outward, each said blade extending through said rim means and having radially extending slots therein receiving said imperforate outer portions of said disks thereinto, fused metal means at said slots fixing each said disk on both sides of the imperforate portion thereof to a said blade, and shaft means supporting said wheel for rotation about said axis, said disks comprising front and rear disks and intermediate disks bridging the gap between said front and rear disks and fixed thereto.

UNITED STATES PATENT OFFICE
CERTIFICATION OF CORRECTION

Patent No. 2,976,011

March 21, 1961

Edward A. Stalker

It is hereby certified that error appears in the above numbered patent requiring correction and that the said Letters Patent should read as corrected below.

Column 2, line 29, after "dies." insert the following:
-- It will be noted that the disks 44, 46, 54 and 56 are peripherally continuous and imperforate in their outer peripheries and over the area which receives the slotted ends of the blades in order to sustain the high centrifugal force encountered in a high speed rotor. Further the blade slots 50, 38, 52 are relatively narrow, of a width substantially the thickness of the disks, so that bonding thereof takes place on both sides of the disk as indicated in the drawings. --.

Signed and sealed this 29th day of August 1961.
